UNITED STATES PATENT OFFICE.

CHARLES LEHMANN AND EDWARD BRUNHOFF, OF CHICAGO, ILLINOIS.

SELF-HEATING SOLDERING-IRON.

SPECIFICATION forming part of Letters Patent No. 448,055, dated March 10, 1891.

Application filed June 9, 1890. Serial No. 354,730. (No model.)

To all whom it may concern:

Be it known that we, CHARLES LEHMANN and EDWARD BRUNHOFF, subjects of the Emperor of Germany, residing at Chicago, in the county of Cook and State of Illinois, have invented certain new and useful Improvements in Self-Heating Soldering-Irons, which are fully set forth in the following specification, reference being had to the accompanying drawings, in which—

Figure 1. represents a side elevation of a soldering-iron embodying our invention, the handle being partly broken away on one side thereof; Fig. 2, a longitudinal section of the lower part of the same, taken on the line 2 2 of Fig. 1; Fig. 3, a plan section of the same, taken on the line 3 3 of Fig. 2; Fig. 4, a similar plan section taken on the line 4 4 of Fig. 2, and Fig. 5 also a similar plan section taken on the line 5 5 of Fig. 2.

Our invention relates to that class of soldering-irons usually termed "self-heating," and more particularly to such irons of this class as are kept hot while in use by the combustion within them of oil, gas, or other suitable fuel.

The object of our invention is to produce an iron of this description which is adapted to the use of gasoline or any other similar liquid fuel by converting it into a gas which is burned in the interior of the head of the soldering-iron, our improvements being intended to completely vaporize the liquid and thoroughly mix it with sufficient air for proper combustion, and also to make the tube perfectly safe for ordinary use.

We will now describe in detail the construction and operation of a soldering-iron in which we have practically embodied our invention, and will then point out more definitely in the claims the particular improvements which we believe to be new and wish to secure by Letters Patent.

In the drawings, A represents the handle of the tool, which also constitutes a reservoir for the gasoline or other liquid fuel. This handle consists of two parts—namely, a tube *a*, of thin metal, open at each end, and a covering or wrapping *a'*, of any suitable material which is a good non-conductor of heat. It may be flax, asbestos, wood, or any other good

non-conducting substance. This covering surrounds the tube and extends its whole length, except a short section at its inner end, which is externally threaded, as seen in Fig. 55 2. The outer end of the tube is internally threaded, as seen in Fig. 1, whereby it is adapted to receive a cap or cover *B*, which is threaded to fit this end of the tube and close it. This cap is cup-shaped and provided with 60 a narrow lateral flange *b*, which fits over the ends of the tube and its outer covering when the cap is screwed down in place, as seen in Fig. 1. The cap also has a central aperture *b'* to permit the filling of the reservoir, and this aperture is threaded and closed by a suitable thumb-screw *b''*. The body *C* of the tool is adapted for the attachment of this handle. This body or central part of the tool is cylindrical, having one portion *c* of a 70 diameter but little less than that of the handle, while at the other end it is diminished in size to form a neck *c'*, which at its extremity is made flaring to correspond in size with the tube *a*, to which it is attached by means of an 75 internal thread corresponding to the external thread on the projecting end of the tube, as seen in Fig. 2. Both these sections of the tube are hollow, but they are separated by a solid bridge *c''* about midway of the body. 80 The hollow section *c* forms a combustion-chamber, while the upper section *c'* makes a continuation of the fuel-reservoir beyond the tube *a*. This body is, however, cast entire, so that these two sections and also the bridge 85 constitute but one single piece. About the center of the body where the bridge occurs a series of apertures *c''* are made, extending downward and inward through the shell into the lower chamber, as seen in Fig. 2, and below these in the section *c* is a series of long slots *c''*, extending lengthwise of this section. There is, therefore, atmospheric connection with the lower chamber through both the apertures *c''* and the longitudinal slots *c''*.

The gas-generator or the device for converting the liquid fuel into gas is arranged within the lower chamber *c*. It consists of a small tube *D*, bent into **U** form and having both ends open. One end of this tube is connected to the lower end of a small passage *d*, which is drilled through the bridge *c''* between

the two chambers, so that connection is thus established between the tube and the fuel-reservoir by means of this hole, which forms an inlet-passage. The other end of the tube 5 is connected to the lower or outer end of a similar small passage d' , drilled directly into the bridge c^2 on the side next to the lower chamber. A regulating-screw E is inserted in the side of the solid central portion of the 10 body, the latter being drilled from the outside opposite to the inlet-passage d , so as to form an aperture e , extending inward and downward slightly and crossing the passage d' at its extreme inner end and extending inward therefrom to about the center of the bridge, as seen in Fig. 2. This aperture e is threaded, so as to receive the screw E, and the latter terminates in a conical point, just behind which there is a shallow annular groove 15 e' , by which construction the screw is adapted to either partly or entirely close the connection between these two passages or fully open it, as desired. A small gas tip or nipple F is fixed in the inner side of the solid bridge c^2 , which 20 is provided with a shallow central socket f for this purpose, the socket and nipple both being threaded to fix the latter in position. There is nothing peculiar about the construction of the nipple, and it is provided with the 25 usual central perforation f' , constricted at the extremity of the tip. A short passage or conduit f^2 connects this nipple with the inner end of the passage e , as seen in Fig. 2, so that there is thus provided an outlet for the tube 30 D by means of the passage-ways $d' e f^2$ and the nipple F, the latter having its outlet directly into the upper or inner part of the combustion-chamber. It will be noticed that all 35 of these passages are drilled in a straight line, so that they may be easily and readily formed, and it will also be noticed that the nipple is arranged centrally of the combustion-chamber between the two ends of the U-shaped tube D. A tube G is arranged between the 40 legs of the U-shaped tube F, to which it is fastened by any suitable means. This tube is open at both ends and extends inward nearly to the nipple F. It is also provided with perforations g, scattered irregularly over 45 its surface. At the lower or outer end of the tube G the small tube D is bent upward or inward, and then around the end of the tube, so that it half incloses the latter by a semi-circular bend d^2 , which is at right angles to 50 the main direction of the tube, as seen in Figs. 2 and 5 of the drawings.

The lower or outer end of the body C is provided with an internal thread, and the soldering-tip H is secured to this end of the body 55 60 65 by a thread on its inner end or base, which is reduced for the purpose of fitting into the section c, as seen in Fig. 2. This tip H is of the usual tapering form; but the base is hollow for a certain distance, it being drilled out or re- 70 75 80 85 90 95 100 105 110 115 120 125 130 135 140 145 150 155 160 165 170 175 below, which forms a combustion-chamber, and the generating-tube and burner located within the combustion-chamber and connecting directly with the passage through the central partition, substantially as and for the purposes specified.

2. In a self-heating soldering-iron, the combustion-chamber, in combination with the **U**-shaped generating-tube D, arranged within said chamber and communicating at one end with the reservoir and at the other with the burner, and the perforated tube G, open at both ends and arranged between the legs of

said **U**-shaped tube, substantially as and for the purposes specified.

CHARLES LEHMANN.
EDWARD BRUNHOFF.
